N. SCHWARTZ

METHOD OR PROCESS FOR PRODUCING KNIT FABRICS

Filed Sept. 25, 1919

Inventor

Nathan Schwartz

By his Attorney

UNITED STATES PATENT OFFICE.

NATHAN SCHWARTZ, OF NEWARK, NEW JERSEY.

METHOD OR PROCESS FOR PRODUCING KNIT FABRICS.

Application filed September 25, 1919. Serial No. 326,285.

To all whom it may concern:

Be it known that I, NATHAN SCHWARTZ, a citizen of the United States, and resident of Newark, in the county of Essex and State 5 of New Jersey, have invented new and useful Improvements in Methods or Processes for Producing Knit Fabrics, of which the following is a specification.

My invention relates to a new and useful method or process for producing knit fabrics.

In knitting and manufacturing textiles such as silk hosiery, silk underwear and other fabrics, the thread commonly runs 15 across the fabric, and each row of loops hangs upon the succeeding row. Under this mode of knitting, if a thread breaks, the stitches or loops quickly unrove, or, as it is commonly termed, "runs down." The 20 thread usually breaks unnoticed, and owing partly to the nature of the silken thread, and partly to the fact that the fabric is stretched tightly upon the wearer, unroving usually takes place so rapidly that the article or garment 25 is in a condition beyond presentable repair before the break is noticed. This is particularly true of ladies' silk hosiery, which are seldom worn out, but which are usually thrown away as useless because of a 30 "run down," due directly to a broken thread.

The object of my invention, therefore, is to provide a new and novel method or process of knitting, in which the old loops, before they are cast off the pins or needles, are 35 interengaged and locked in such manner that when the thread breaks, unroving cannot take place beyond the next succeeding interengaged or locked loop. Under my improved mode of knitting, the thread runs 40 across the fabric the same as before, and each row of loops hangs upon the succeeding row the same as before, but every other stitch or loop is interengaged or locked with its neighbor alternately in succeeding rows, 45 or, if desired, the stitches or loops may be interengaged or locked at certain intervals alternately in succeeding rows.

Further objects of my invention will hereinafter appear.

50 The subject matter of the present invention is also described in and certain features of the invention herein described, but not herein claimed, are claimed in my companion application for patent filed November 11, 1919, Serial No. 337,224.

55 The invention consists in the novel

method or process herein described and more particularly pointed out in the claims.

The figure in the accompanying drawing represents a plan view of a portion of silk 60 fabric as produced in accordance with my improved mode of knitting.

In the accompanying drawing, the thread in alternate succeeding courses has been shown as white and black, respectively, the 65 white thread being employed to represent the interlocking courses and the black thread to represent the plain courses. Alphabetical characters are employed to designate corresponding cross rows of stitches or 70 loops, each cross row consisting of a white or interlocking course and a black or plain course while similar numerals are employed to designate the individual stitches or loops, corresponding as to position, that make up 75 the interlocking courses.

It is, of course, common knowledge, that in hand knitting and framework, as well as in machine knitting accomplished on well known types of straight bar knitting machines and on some circular and flat knitting machines, the thread runs across the fabric, and the old loops or row of loops are cast off to hang upon the new loops or succeeding row of loops. These principles hold 80 good in my improved mode of knitting.

In my improved mode of knitting, I have contrived to produce a non-ravelling fabric by first interengaging or locking either every other stitch or loop or certain interval 85 stitches or loops in the first row, then alternating the system of interengaging or locking in the second row, and so on similarly interengaging and alternating throughout the succeeding rows.

Thus in the accompanying drawing, let the characters A, B and C represent succeeding cross rows of loops and the numerals 3, 4, 5, 6 and 7 represent the successive loops of each interlocking course. Consider first 100 the method of interengaging or locking every other loop. In row A, for instance, there is shown a course of plain (black) loops, then a course of interlocking (white) loops. In knitting the interlocking course, 105 plain loops are first formed, and then, before the same are cast off their needles, loop 3 is spread and hung one-half of it alongside loop 4 on the needle carrying loop 4. Loop 4 is skipped; but loop 5 is similarly spread and one-half of it hung alongside loop 6 on the needle carrying loop 6. Loop 6 is 110

skipped, and loop 7 is divided and spread one-half of it on its next succeeding neighbor, (not shown) and so on throughout the length of the row. From this method of procedure, it will be understood at once that one-half of a loop hangs from every other needle (in the knit fabric from every other loop immediately above), while a loop and a half hangs from every other succeeding needle (in the knit fabric from every other succeeding loop immediately above), and that in thus spreading every other loop the thread thereof is engaged over, tightened and locked upon the undivided loop.

In row B, loop 3 is skipped, since in row A the corresponding loop 3 was locked with loop 4. In row B, loop 4 is spread and hung upon the needle carrying loop 5, since in row A, loop 4 was skipped and left un-divided. And so on similarly throughout row B, the alternates of row A are divided and spread over two needles. In row C, loops 4, 6 and so on, are skipped in correspondence with the skips made in row A, the same representing the alternates of row B. In this manner I proceed to knit the whole fabric, dividing, spreading and interlocking every other loop alternately in succeeding rows.

This method of spreading, interlocking and skipping loops alternately in successive rows may be employed in a variety of forms, which readily suggest themselves. Thus, in the first row, instead of skipping loops 4 and 6, as above described, loops 4 and 5 may be skipped, loop 6 spread and interlocked, the two loops following 6 skipped, and so on progressively skipping by consecutive twos throughout the row. In row B, loop 4 would be spread and interlocked, loops 5 and 6 skipped; and so on along the row, spreading and interlocking one loop and skipping two loops. In row C, loop 5 is locked and spread, loops 6 and 7 skipped, and so on as before. With this form, in row A, loop 3 is interlocked with loop 4; in row B, loop 4 is interlocked with loop 5; and in row C, loop 5 is interlocked with loop 6. Should a thread break, only two stitches or loops can unravel.

In a similar manner, three, four, five or any desired number of consecutive loops

may be skipped in each row, the spreading and interlocking taking place at equivalent intervals. In this connection, it will be understood, that if a thread breaks where three loops are skipped, three loops only will unravel, if it breaks where four loops are skipped, four loops will unravel. So, in the use of the various forms that will readily suggest themselves, unravelling can only take place in correspondence to the number of loops skipped.

Having thus described my invention, what I claim is:

1. That improved method or process of knitting which consists in forming plain courses and interlocking courses, the interlocking courses being formed by spreading, interlocking and skipping loops alternately in succeeding interlocking courses.

2. That improved method or process of knitting which consists in forming plain courses and interlocking courses, the interlocking courses being formed by spreading, interlocking, and skipping loops at equivalent intervals, alternately in succeeding interlocking courses.

3. That improved method or process of knitting which consists in forming plain courses and interlocking courses alternately in succeeding rows, the interlocking courses being formed by spreading, interlocking and skipping loops systematically by alternates in succeeding interlocking courses.

4. That improved method or process of knitting which consists in forming plain courses and interlocking courses, the interlocking courses being formed by spreading and interlocking every other loop with its neighbor and in skipping every other loop, symmetrically by alternates in succeeding interlocking courses.

5. A knitted fabric comprising rows of loops, each row consisting of a plain course and an interlocking course, each interlocking course being formed by spreading and interlocking certain loops with their neighbors and in skipping one or more loops, symmetrically by alternates in succeeding rows.

In testimony whereof I have signed my name to this specification.

NATHAN SCHWARTZ.
